UNITED STATES PATENT OFFICE.

HENRY P. KINGSLAND, OF NEW YORK, N. Y.

DESIGN FOR A SLIPPER.

SPECIFICATION forming part of Design No. 31,422, dated August 15, 1899.

Application filed June 3, 1899. Serial No. 719,310. Term of patent 14 years.

To all whom it may concern:

Be it known that I, HENRY P. KINGSLAND, a citizen of the United States, residing at 102 East Nineteenth street, New York, in the county of New York, State of New York, have invented and produced a new and original Design for Slippers, of which the following is a specification, reference being had to the accompanying drawings, forming part thereof.

Figure 1 is a perspective view of a slipper embodying my design, and Fig. 2 is a side elevation of the same.

The reference-letter *a* designates the sole of the slipper, which is straight or horizontal, as shown in Fig. 2, and rounded at its front and rear ends *b* and *c*. The rear end portion of the upper *B* of the slipper is inclined forward, as shown at *d*.

The heel portion or counter *D* of the slipper, which constitutes the leading feature of the design, is curved downwardly or concaved at the center *e* of its upper edge, and said counter inclines forwardly, as shown at *f*. The side edges *g* of the counter *D* are curved or rounded, as clearly shown.

Having described my invention, what I claim, and desire to secure by Letters Patent, is—

The design for a slipper, as herein shown and described.

HENRY P. KINGSLAND.
